PLAYING CARD

Roy W. Middlebrook, Metuchen, N. J.

Application August 12, 1940, Serial No. 352,207

1 Claim. (Cl. 273—152)

This invention relates to playing cards and, more particularly, to playing cards to be used for playing contract bridge, duplicate contract bridge, whist or like games.

It is the custom in duplicate contract bridge, to use a set of thirty-two boards each having therein four pockets, one for each player. A pack of ordinary playing cards is used for each board and in playing the game four hands are dealt, one card at a time being dealt in rotation to each of the pockets on the board into which the cards are placed. This is repeated until each pocket in every one of the thirty-two boards contains a hand of thirteen cards. The players then take their positions at the table and start the game by taking the hand on the board in the pocket which is designated for the player at his particular position. The game is then played in accordance with the regular rules for playing duplicate contract, duplicate auction or duplicate whist. The cards, however, are not played in the center of the table but each card is placed in front of the particular player from whose pocket it was drawn, so that when the hand is completed the respective hands may be replaced in the pockets from which they were drawn. Tricks are credited to the players taking them and the score for the hand is counted, premiums and penalties being rewarded in accordance with a schedule on the board. In other words, each board has indicated thereon which side is vulnerable and which side is not on the hands played from that board.

The vulnerability, non-vulnerability and dealer change with each hand played, the schedule on each board, therefore, being different.

The above procedure is repeated until all thirty-two boards have been played. The boards are then replayed by one pair of players exchanging places with the other pair, so that during the play of the next thirty-two boards one pair of partners will play the hands played by their opponents on the first round.

In playing duplicate bridge, or whist, as it is now played, a great deal of equipment in the way of decks of cards and boards is required, the expense of which is prohibitive to a great many players desiring to play this game.

It is an object of the invention to provide a deck of ordinary playing cards with which duplicate bridge may be played in a manner natural to a player accustomed to playing ordinary bridge.

Another object of this invention is to provide a deck of cards to be used for playing duplicate bridge which will do away with all paraphernalia

now used in playing such a game with the exception of one deck of cards.

Another object of this invention is to provide a deck of ordinary playing cards on the back of which is indicated the dealer and the vulnerability of the various players on each particular hand of a series of hands of contract bridge, duplicate contract bridge, whist or like card game to be played.

A still further object of this invention is to provide a playing card on which the vulnerability of the various players on each hand of a series of hands to be played is permanently indicated and on which each player may mark by a removable mark his position when a card is dealt to him so that the card on a subsequent deal may be dealt to that same position and played by another player after the players have changed positions, the mark being removable thereafter.

Other objects of the invention will become apparent in the course of the following specification.

The above and other objects of the present invention may be realized by providing a deck of ordinary playing cards having the back thereof divided into a plurality of enclosed areas each being marked to indicate one game of a series of games to be played, each enclosed area having four positions designated therein, each of the four designations representing the position occupied by the various players of a bridge, whist or like game, and each designation being marked to designate the dealer, the vulnerability and non-vulnerability of each individual player on any one given hand of a series of hands being played. The card is also adapted to be marked so as to indicate the position to which it is dealt so that it may on a subsequent hand be re-dealt to that same position.

The invention will appear more clearly from the following detailed description when taken in connection with the accompanying drawing, showing by way of example a preferred embodiment of the invention, together with possible modifications thereof.

In the drawing:

Figure 1 is a perspective view of a deck of cards showing in elevation the back of one of the playing cards;

Figure 2 is a view similar to Figure 1 of a modification of this invention;

Figure 3 is a view similar to Figure 1 of a further modification of the invention.

In the embodiment of the present invention, shown in Figures 2 and 3 of the drawing, a pack

a of ordinary playing cards is used. The backs *b* of each one of these cards has imprinted thereon a plurality of enclosed areas *c* which are preferably square.

Each square *c* has four positions W, N, E and S designated therein each of these designations representing a position occupied by a player. As illustrated in the drawing, each square *c* is divided into four parts by two diagonal lines each extending from one corner of the square to the diagonally opposite corner dividing the squares *c* into four equilateral triangles each triangle representing a position occupied by a player.

The triangles designating positions W, N, E and S are each marked to indicate which player or players are vulnerable, which ones are not vulnerable, and to indicate which player is the dealer during the playing of each different hand. In the drawing, different colors are used for such markings but it will be readily understood that other indicative markings may be used. For example, the symbol for red indicates vulnerability; black indicates, non-vulnerability and the symbol for yellow indicates the dealer.

Each enclosed area *c* represents one hand of a series of hands of a game of duplicate bridge, bridge, whist or other like card game to be played and is marked, preferably, by a number *d*. Since each enclosed area *c* represents a different hand of a game of cards to be played, a different number *d* is used for each area.

In the drawing, the areas *c* are arranged in parallel lines, extending vertically and transversely on the back of the cards. The areas *c* are numbered consecutively from left to right transversely on the card, the lowest number being at the left of the top line in the drawing and the highest at the right. The next lower line of squares *c* are likewise numbered, the first square in the line being the next consecutive number higher than the last number of the preceding line.

Since different positions are vulnerable or non-vulnerable during the playing on each hand, and since there is a different dealer on each hand, these differences are indicated by coloring the triangles W, N, E and S. The player, therefore, may ascertain which positions are vulnerable, which are not vulnerable and which position dealt the given hand by looking in the enclosed area *c*, the number *d* which corresponds to the number of the given hand.

In the embodiment of the invention shown in Figure 1, the back *b* of each card in the deck is arranged to indicate which position will deal the cards in each one of sixteen hands and, also, which positions will not be vulnerable during the playing of each one of the sixteen hands. The back of the card is divided transversely through the center thereof into two parts *x* and *y*, each part having sixteen squares *c* arranged in four lines or arranged in four vertically and horizontally extending lines, each having four squares therein. The squares are numbered consecutively from left to right, beginning at the left hand square on the top line, a corresponding square *c* of each half *x* and *y* bearing identical numbers and markings.

The embodiment shown in Figure 2 illustrates the backing of the playing card marked to designate the dealer, the vulnerability, the non-vulnerability of the different positions W, N, E and S of each hand in a series of thirty-two hands to be played. The vulnerability, non-vulnerability and dealer are indicated in color similar

to that used in Figure 1. The number *d*, however, designated the hand numbers are enclosed in diamond-shaped enclosures. The card is likewise divided into an upper section *x* and a lower section *y*, the area *c* in the upper section being arranged and numbered in a manner similar to the playing areas in the embodiment shown in Figure 1. The area *c* of the lower half are numbered, however, from 17 to 32.

In the embodiment of the invention shown in Figure 3, the vulnerability of the various players are designated by letters.

The back of the card is divided into two halves *x* and *y* each half *x* and *y* being divided vertically into four parts, a vertically extending line *z* dividing the four parts in the center. Each half is, therefore, divided into eight enclosed areas, each area representing one hand of cards to be played. It will be readily understood that the back of the card may be divided into either more or less areas according to the number of hands in the series of hands in the game for which the card is to be used.

Each area is numbered at *r*. A letter is imprinted adjacent the number at *s* the letter indicating one of the four positions, North, South, East or West, the position to which the card is to be dealt in the hand corresponding to the adjacent number. These letters may be either permanently or removably imprinted on the card.

At the top of each column of enclosed areas is the letter D, and in each area under this letter is a letter corresponding to one of the positions at a bridge table, these letters indicating the dealer on the hand corresponding to the number adjacent the letter.

Adjacent the indicia denoting the dealer are letters indicating which positions at the table are vulnerable.

In playing a game of duplicate bridge with the cards of this invention, the cards are dealt from the pack to the player occupying each position W, N, E and S, one at a time in rotation, as is the usual custom playing this game. Each player will then designate his position by any desired mark by placing this mark on the back of each card which he holds preferably in the margin as designated by the reference letter F. The cards are, preferably, of a washable material, so that the marks placed on them in this manner may be easily removed when desired. The cards are then played in accordance with the usual procedure in a bridge game, each player winning a trick taking that trick from the center of the board, placing the same opposite him, as is usual in an ordinary bridge game. The game is then scored in accordance with the usual bridge rules. The awards and penalties are scored in accordance with the vulnerability or non-vulnerability of the various players which may be ascertained by referring to the back of any one of the playing cards and looking at the area *c* bearing the number corresponding to the number of the hand just played. In a series of hands to be played, for example, we shall consider the hand just played, as hand No. 1, in a series of sixteen hands to be played, by referring to Figure 1 of the drawing, it will be seen that in the area or square *c* appearing adjacent the numeral 1, W, N, and E are not vulnerable and that S was the dealer. Referring to the next hand to be played, hand No. 2, by looking in the square on the chart on the back of the card to the right of the numeral 2, it will be noted that W is the dealer, N and S are vulnerable and E is not vulnerable.

The vulnerability and non-vulnerability of the different players in the various hands of play follow the standard contract bridge board schedule.

In the embodiment of the invention shown in Figure 2 of the drawing, the back of the card is marked for use in playing a series of thirty-two games. The series are numbered by small numbers appearing in diamond-shaped enclosures.

It is apparent that the specific illustrations shown have been given by way of illustration and not by way of limitation and that the structure above described is departing from the scope or intent of the invention, all of which variations and modifications are to be included within the scope of the present invention.

What is claimed is:

A card for playing duplicate bridge having the entire back surface thereof divided into two groups of 16 enclosed square-shaped areas each representing a bridge hand and having indicia 20

5 indicating the round, each of said areas being divided into four triangular sections each representing a player, a second square-shaped area centrally disposed within said first-mentioned square-shaped area and being of such size that there is sufficient space between the sides of said first-mentioned square-shaped area and said second-mentioned square shaped area to make notations therein, said second square-shaped area being divided into four equilateral triangular sections coinciding with the triangular sections of said first-mentioned area one of said triangular sections having indicia indicating the dealer, the opposite section having indicia indicating the vulnerability or non-vulnerability of the partner and the two remaining opposite sections having indicia indicating the vulnerability or non-vulnerability of the opponents.

ROY W. MIDDLEBROOK.
